UNITED STATES PATENT OFFICE.

ALBERT HAMPE, OF STAUNTON, ILLINOIS.

RUNNING-GEAR FOR WAGONS.

SPECIFICATION forming part of Letters Patent No. 231,562, dated August 24, 1880.

Application filed April 30, 1880. (No model.)

To all whom it may concern:

Be it known that I, ALBERT HAMPE, of Staunton, in the county of Macoupin and State of Illinois, have invented certain new and 5 useful Improvements in Coupling-Poles for Spring-Wagons, of which the following is a specification.

In the accompanying drawings, Figure 1 represents a bottom view, Fig. 2 a side view, 10 and Fig. 3 a vertical transverse section on line $x\ x$, Fig. 1, of a spring-wagon with my improved coupling-pole. Fig. 4 is a detail vertical longitudinal section of the coupling which connects the front and rear part of the pole. 15 Fig. 5 is a sectional side view of a wagon with a modified form of coupling, and Fig. 6 is a vertical transverse section of the same on line $y\ y$, Fig. 5.

Similar letters of reference indicate corresponding parts.

This invention relates to an improved coupling-pole for buggies and spring-wagons, which is specially adapted for the heavier class of wagons used by farmers and others.

25 By the use of the improved coupling-pole the wagon is drawn by the horses with less effort over rough and cut-up roads, is less liable to injury and breakage, and more durable in every respect.

30 The invention consists of a coupling-pole made of two sections, which are connected by a coupling of suitable construction, so that each pole-section has independent axial play. The body of the wagon is connected to the coupling-pole by a hinged center rod and bracing side straps, while the front spring is capable of laterally-oscillating motion by being hinged either to the front head-block or to the wagon-body.

40 Referring to the drawings, A represents the body of a spring-wagon, and B the coupling-pole, which extends from the front head-block, C, to the rear axle. The coupling-pole B is made of two parts or sections, a shorter front 45 and a longer rear section. These sections are connected by a coupling, D, which is constructed in such a manner that each pole-section has an independent axial play, so as to follow or yield to the motions of the front and 50 hind axles when they assume a laterally-in-

clined position in passing over rough parts of the roads.

The coupling D may be of any approved construction, it consisting, mainly, of a center pin which connects the end mountings of the pole-sections, as shown in Figs. 4 and 6.

The hind end of the rear pole-section is firmly attached to the rear axle by side braces, $a\ a$, while the front section of the pole is rigidly connected by straps $b\ b$ to the front head-block, 60 C. The body A is connected either to the front section of the pole B, as shown in Fig. 2, or to an intermediate portion of the coupling D, as shown in Fig. 5, by a center rod, E, which is hinged to the bottom of the wagon at d . 65 The lower end of the rod D passes through a hole of the front pole-section or of the coupling, and is further connected by leather or metal straps E' to the sides of the wagon. The elliptical front spring, F, is either hinged at 70 its lower portion to a strap, d, of the front head-block, being rigidly secured by its top portion to a bolster at the under side of the wagon-body, as shown clearly in Fig. 3, or the lower part of the spring E is rigidly affixed to the 75 front head-block and hinged at its upper part by an intermediate link, e, to a strap, d, of the spring E, the link being pivoted at its opposite ends to fixed lugs e' of the wagon-body. Either construction imparts a certain flexibility to the front part of the wagon, so as to render it liable in a less degree to injury by sudden jars or strains exerted thereon in passing over rough roads.

By the axial play of the pole-sections and 85 the facility by which the front spring follows the front axle both axles may assume a laterally-inclined position without affecting the load, as heretofore. The wagon is thereby less affected by rough roads, and at the same time 90 its rigid connection with the coupling-pole retained by the hinged center rod and connecting side straps.

Having thus described my invention, I claim as new and desire to secure by Letters 95 Patent—

1. The combination of a coupling-pole made in two sections, which are connected by a coupling, for admitting the axial motion of the sections, with a hinged center rod and side 100

straps of the wagon-body, substantially as specified.

2. The combination, in a spring-wagon, of the body A and front head, C, with an elliptic front spring, F, which is interposed between body and bolster, and attached rigidly at one center point to the body or bolster, and connected by a laterally-swinging hinge to the body or bolster at the other center point, substantially as set forth.

3. In a spring-wagon, the combination of the body A, having fixed lugs c', with the front

spring, F, which is pivotally connected to the lugs by a hinged link and rigidly affixed to the front head-block, for the purpose described. 15

In testimony that I claim the foregoing as my invention I have signed my name, in presence of two witnesses, this 23d day of April, 1880.

ALBERT HAMPE.
